[57] **CLAIM**

The ornamental design for a combined mug and megaphone, as shown and described.

DESCRIPTION

FIG. 1 is a front, top and right side perspective view of a combined mug and megaphone showing my new design;

FIG. 2 is a top plan view;

FIG. 3 is a bottom plan view;

FIG. 4 is a partially cut away right side elevational view, the left side being a mirror image of the right;

FIG. 5 is a front elevational view; and

FIG. 6 is a rear elevational view.
